ATTORNEY

UNITED STATES PATENT OFFICE.

STEVE BULLUM, OF SAN LUIS OBISPO, CALIFORNIA.

CLAMP.

1,396,353.

Specification of Letters Patent.

Patented Nov. 8, 1921.

Application filed April 26, 1921. Serial No. 464,732.

To all whom it may concern:

Be it known that I, STEVE BULLUM, a citizen of the United States, residing at San Luis Obispo, in the county of San Luis Obispo and State of California, have invented new and useful Improvements in Clamps, of which the following is a specification.

This invention relates to oil well tools and particularly to cable clamps. Said clamp is an improvement on the device set forth in my application for wire line clamp, Serial No. 410,516, filed September 15, 1920, in the U. S. Patent Office.

15 The invention has for an object the provision in a clamp of means for preventing excessive rotation of the jaw members of said clamp and likewise of means for causing registration of said jaw members. Another object of the invention is to provide means for preventing stripping of threaded elements used in practising the invention.

In practising the invention I provide a link member formed with enlarged knuckles 25 at its ends, to which link member two jaw members are pivotally joined. Said jaw members are likewise provided with a suspension means in the form of a hook or lug whereby the entire device may be suspended 30 from a supporting rigging. Said jaw members are bifurcated at their free ends and between the bifurcated portions are received means for relatively adjusting the jaw members and for maintaining the same in such 35 adjusted position. The link member is provided with outstanding studs which are adapted to contact with the outer surfaces of said jaw members to limit the rotation and opening movement of the jaw members

40 about their pivot points. Likewise there is carried by one of the jaw members a stud member adapted to be received within a recess in the opposite jaw member. The stud member acts to equalize the amount of 45 angular movement of the jaws and likewise to insure registration of slip members or liners, which are carried by the jaws, when the jaws are closed.

The invention has for further objects the provision of an improved clamp which will be superior in point of relative simplicity and inexpensiveness, taken in conjunction with utility, durability and general efficiency and serviceability.

55 With the above mentioned and other ob-

jects in view, the invention consists in the novel and useful provision, formation, construction, combination, association and interrelation of parts, members and features, as illustrated in some of its embodiments in the accompanying drawing, described in the following detailed description, and finally pointed out in claims.

In the drawing:

Figure 1 is a fragmentary side elevation of my improved clamp constructed in accordance with the present invention;

Fig. 2 is a fragmentary front elevation of the improved clamp;

Fig. 3 is a top plan view of the improved clamp;

Fig. 4 is an isometric view of a screw socket member used in practising the invention;

Fig. 5 is a cross sectional view of one of the gripping members, the said view being taken on the line 5—5, of Fig. 1; and

Fig. 6 is a perspective view of the link member used for connecting the respective jaw members of the improved clamp.

Corresponding parts in all the figures are designated by the same reference characters.

Referring with particularity to the drawing wherein I have illustrated a preferred form of the invention, A designates the improved clamp in its entirety, and B represents the jaw members, and C means for opening or closing the jaw members. The jaw members B may be designated as 1 and 2, and each is provided with enlarged portions 3 and 4, and said enlarged portions are bifurcated for a portion, as shown at 5 and 6 (see Figs. 1 and 2). Received between the bifurcated portions is a link member a which is held in the bifurcations by means of pins 7 and 8 passing through aligned perforations in the jaw members and in the link member a. It will thus be seen that the jaw members may be pivoted around said pin so as to open same. The jaw members 1 and 2 outward from the enlarged portions of the jaws are narrowed and of extended length, as shown at 9 and 10. Each of the members 9 and 10, as shown at 11 and 12 is bifurcated to form two lugs 13 and 14 for the confinement of screw socket members b.

The jaw members are each provided with hook or lug members c which are preferably integrally formed with the respective jaw 110

members. Said hook members are adapted to confine link members *d* which are joined with the supporting rigging, not shown.

In each jaw, in alignment with the respective hook or lug member *c* is formed recesses 16 and 17 within which gripping members or liners or slips *e* are adapted to be received. The jaws are likewise recessed as at 18 and 19 to receive a shouldered portion 20 of each of the slips *e*. A screw member 21 is adapted to pass through a perforation in each of the jaw members and have screw-threaded engagement with a threaded perforation extending through the shouldered portion 20 of the slips, as shown at 22, for holding the slip members in position. It is obvious that the shouldered portion when confined within the recess will prevent a shearing action upon the screw members 21.

It is also to be noted that each respective jaw member is formed with depending extensions 23 and 24 so as to entirely inclose the respective slips or liners.

If it were desired to open the jaw members, it is obvious that a link-work consisting merely of two jaws pivoted to the free ends of a link member *a*, might cause the mechanism to shift or rack. To prevent this I provide on one of the jaw members an outstanding pin or lug 25 adapted to be received within a recess 26 in the other jaw member. Now, as the jaw members open and close the pin member may be received within the recess 26 and at all times control the two jaw members so that they may have equal angular movement with respect to the connecting link *a*. Hence, it is unnecessary for a well operator to exercise any particular care in operating the clamp A to see that the slips *e* register when the jaws are closed, this being accomplished by the means shown.

Another important feature of the stud or lug 25 is that it is placed adjacent the slips *e* and its position tends to prevent the cable from passing beyond the slips *e* and against the link member. Obviously, placing the stud adjacent the slips would tend to direct the cable always within the confines of the slips when the jaw members are being closed.

I likewise provide means associated with the link member *a* for preventing an excessive opening movement of the jaw members. This is accomplished by providing on the knuckle portions of said link outstanding projections 27 and 28, which projections, as shown in Fig. 3, will contact with the surface at 29 and 30 of the respective jaw members and limit the opening movement, as is obvious.

The means *C* is disposed transversely of the free ends of the jaws and operable to relatively adjust the same and to hold the same in such adjusted position. Said means includes a handle member 31 carrying a screw member 32 at right angles thereto.

Said screw member is provided with right and left-hand threads, as shown at 33 and 34. Between the lug members 14 and 15 of the jaw member 10 is received the screw socket member *b*, which member is formed with trunnions 35 and 36 received within sockets contained within the lug members 14 and 15, as shown in Fig. 2 by dotted lines at 37 and 38. The opposite jaw member 9 is not provided with bearings or sockets, but on the contrary is formed with concave recesses as shown at 39 and 40. A further screw socket *b* has its trunnions 35 and 36 adapted to be received within the concave recesses 39 and 40. The screw socket members *b* are adapted to be threaded upon the threaded portions 33 and 34 of the operating handle *C*, so that upon turning the handle member 31 the socket members would move in opposite directions either away from each other or toward each other. Obviously to release the jaw members a proper turning of the operating handle 31 will cause the screw socket member *b* which has its trunnion ends received within the concave recesses, to be freed from said recesses, at which time the handle member in its entirety may be revolved about the trunnions of the screw socket member carried by the jaw member 10. In order to prevent the stripping of the threads of the means *C* and likewise to insure that the screw socket members will always be properly received within the bifurcated portions of each of the jaw members, the screw socket members are each provided on a face thereof with an outstanding lug or ear 41. The member *b* which is journaled to the lugs 14 and 15 has its lug 41 provided with a screw threaded perforation 42, while the other member *b* adapted to contact and operate with the jaw member 9, does not have its lug member 41 screw-threaded, but is simply provided with an enlarged perforation 43. A rod member 44 screw-threaded at one end thereof is adapted to pass through the perforation 43 of the socket member *b* and engage the screw-threaded perforation 42 of the member *b* carried by the jaw 10. It will thus be seen that I have provided several novel features in my improved clamp wherein I have provided a link member to which two jaw members are pivotally connected. Said link member carries means for preventing excessive rotation of the jaw members about their pivots and the said jaw members are provided with means for equalizing the amount of angular movement of the same about their pivots so as to insure a registering of the slips when the jaws are closed. I have likewise provided novel means for preventing stripping of the threads of the operating handle *C*.

It is obvious that many changes and variations and modifications may be made in de-

parture from the particular description and showing of the accompanying drawing, in adapting the invention to varying conditions and requirements of use and service, 5 without departing from the true spirit of the invention.

Having thus disclosed my invention, I claim and desire to secure by Letters Patent:

10 1. A cable clamp, including a link; jaw members pivoted to said link; slips carried by the jaw members and adapted to grip the cable between them; means to insure registration of the slips when the jaws are closed, and means for relatively adjusting the jaw members and for maintaining the same in such adjustment; said first named means comprising a stud carried by one of the jaw members, there being a recess in the 15 other jaw member for confining and directing movement of said stud; said stud being adjacent the slip members thereby directing the cable between the slips; said link being provided with means adapted to 20 limit rotation of the jaws about their pivots.

2. A cable clamp, including a link; jaw members pivoted to said link; slips carried by the jaw members and adapted to grip the cable between them; means for relatively adjusting the jaw members and for maintaining the same in such adjustment; said link member being provided with studs adapted to contact with the jaws to limit rotation of the jaws about their pivots.

3. A cable clamp, including a link; jaw members pivoted to said link; slips carried by the jaw members and adapted to grip the cable between them; a stud carried by one of the jaw members, the other jaw member being formed with a recess therein adapted to confine and direct movement of said stud, said members provided on the link member adapted to contact with the jaws to limit rotation of the jaws about their pivots 40 and to prevent the stud member carried by the jaw member from being entirely withdrawn from the recess in the other jaw member; and means for relatively adjusting the jaw members and for maintaining the same in such adjustment.

4. A cable clamp, including a link; jaw members pivoted to said link; slips carried by the jaw members and adapted to grip the cable between them; and means for relatively adjusting the jaw members and for maintaining the same in such adjustment; said jaw members being bifurcated at their free ends, and the said means for relatively adjusting the jaw members including screw 55 socket members received between said bifurcated ends; one of said screw socket members being swivelly mounted in the bifurcated portion of one of the jaws, the other jaw member being formed with a grooved

extremity, with the screw socket member 65 in said jaw provided with means for engaging said grooved extremity; there being an oppositely pitched screw in engagement with said screw socket members whereby the jaws may be opened or closed; said 70 screw socket members each being provided with a perforated ear, there being a guide rod passing through said perforated ears for maintaining the screw socket members in alinement.

5. A cable clamp, including a link; jaw members pivoted to said link; slips carried by the jaw members and adapted to grip the cable between them; studs carried by the link members adapted to contact with the jaws to limit the opening of said jaws, and means for relatively adjusting the jaw members and for maintaining the same in such adjustment; said means including a screw socket member carried by one of the 80 jaw members, and a screw socket member detachably carried by the other jaw member, there being an oppositely pitched screw for engagement with the screw socket members for opening and closing the same; each of 85 said screw socket members being provided with a perforated ear, there being a guide rod passing through said perforated ears for maintaining the screw socket members in alinement.

6. A cable clamp, including a link; jaw members pivoted to said link; slips carried by the jaw members and adapted to grip the cable between them; screw socket members provided with trunnion ends, an oppositely pitched screw in engagement with said screw socket members, one of said screw socket members being mounted in one of said jaws, and the other screw socket member being adapted to detachably engage a 100 grooved extremity in the opposite jaw member; each of said screw socket members being provided with a perforated ear, and a guide rod passing through said perforated ears for maintaining the screw socket members in alinement and for preventing stripping of the threads of the screw socket members and the oppositely pitched screw.

7. A cable clamp, including a link; jaw members pivoted to said link; and means for relatively adjusting the jaw members and for maintaining the same in such adjustment; said link being provided with means adapted to limit rotation of the jaws about their pivots.

In testimony whereof, I have signed my name to this specification in the presence of two subscribing witnesses.

STEVE BULLUM.
